UNITED STATES PATENT OFFICE.

LEOPOLD M. REBEL, OF PARIS, FRANCE, ASSIGNOR TO ISABEY-PARIS INCORPORATED, A CORPORATION OF DELAWARE.

DESIGN FOR A BOX FOR HOLDING PERFUME BOTTLES.

Application filed March 9, 1929. Serial No. 30,403. Term of patent 14 years.

To all whom it may concern:

Be it known that I, LEOPOLD M. REBEL, a citizen of the Republic of France, residing at Paris, France, have invented a new, original, and ornamental Design for a Box for Holding Perfume Bottles, of which the following is a specification, reference being had to the accompanying drawing, forming a part thereof.

In the drawing,

Fig. 1 is a front perspective view of my design,

Fig. 2 is a side view thereof, and

Fig. 3 is a top view thereof.

I claim:

The ornamental design for a box for holding perfume bottles substantially as shown.

LEOPOLD M. REBEL.
